WELTING

William C. Vizard, Brockton, Mass., assignor to
 Barbour Welting Company, Brockton, Mass., a
 co-partnership composed of Perley E. Barbour,
 Walter G. Barbour, and Richard H. Barbour

Application May 16, 1940, Serial No. 335,528

9 Claims. (Cl. 12—146)

This invention relates to welting for shoes, and to its method of manufacture, and more especially to the production of "beaded welting" of the type wherein a bead is formed on the upper face of the welting by folding a flop of the material of the welting, the bead being supported and held in position at the inner edge of the welt extension by an integral part of the flap.

In order to provide sufficient stock for forming the flap which is folded to provide the bead, a fillet must be used which is wider than the finished welt. In my prior Patents Nos. 2,142,228 and 2,153,321 I have disclosed and claimed certain methods of severing and slitting a double fillet in such manner that two single fillets are formed, the total width of the two single fillets, prior to folding of the flaps, being greater than the initial width of the double fillet before the same is slit and severed. In this way I have been able to effect a great saving in the cost of manufacture of welting as, where thousands and even millions of yards of welting are made, the reduction of the width of a fillet even by a fraction of an inch will result in substantial reductions in cost. In certain aspects the present invention may be regarded as an improvement over my prior patents and has as one of its principal objects an improved method of manufacture of beaded welting from a double fillet wherein still further savings in stock are effected.

A feature of the invention resides in a method of slitting and severing a double fillet of stock to form two strands of welting wherein the width of the double fillet used is reduced to a minimum and is no greater than the combined widths of the two strands of finished welting formed therefrom.

Welting for shoes is commonly made out of grain leather and one of the further objects of the invention is to bring about a form of beaded welting and a method of making the same wherein in two strands of the same made from a double fillet may be provided with beads, as well as welt extensions, having substantially uniform grain leather surfaces capable of matching the finish of the upper leather.

In order that the inner or sewing edge of the welting may not be unduly weakened by the formation of the flap which is folded to form the bead, as well as to preserve grain leather surfaces on the beads, it is proposed herein to make the flaps relatively thin and one of the further features of the invention resides in a form of bead and method of making the same wherein the bead may be given a desired shape and thickness

or weight notwithstanding the thickness of the material entering into the flap.

In the formation of the beads, as described immediately above, I propose to fold the flaps around or about what may be termed bead fillers or cores and another feature of the invention resides in certain novel methods of production and use of these cores during the forming of the beads as more fully described hereinafter.

To these and other ends the invention resides in the novel features and combinations of parts to be hereafter described and claimed, reference being had to the drawing in which:

Fig. 1 is a perspective view of a double fillet showing the method of slitting the same to form two overlapping flaps in accordance with one form of the invention;

Fig. 2 is an end view of the fillet of Fig. 1 and showing one of the flaps raised ready for folding to form a bead;

Fig. 3 is an end view of the fillet of Fig. 1, in this instance both flaps being raised and the bead fillers or cores assembled in place ready for folding of the flaps into final position;

Fig. 4 is an end view of the fillet of Fig. 1 but showing the beads completely shaped ready for cutting of the fillet along a central longitudinal line into two strands of welting;

Fig. 5 is a perspective view of a core piece showing a method of slitting the same to form two lengths of stock suitable for forming the fillers or cores of the beads of Fig. 4;

Fig. 6 is an end view of a fillet similar to that of Fig. 1 but illustrating another method of cutting the double fillet in a longitudinal direction to form two single fillets together with a length of stock suitable for formation of the fillers or cores of the beads;

Fig. 7 is a perspective view illustrative of the manner in which the stock of Fig. 6 is slit to form the two fillers or cores for the beads;

Fig. 8 is a perspective view of a double fillet similar to Fig. 1 but illustrating a modified method of slitting and cutting the fillet longitudinally to form two single fillets;

Fig. 9 is a perspective view illustrative of the further treatment of the single fillet at the left of Fig. 8 prior to forming-up of the bead;

Fig. 10 is a view similar to Fig. 9 but illustrative of the further treatment of the single fillet at the right of Fig. 8 prior to forming-up of the bead; and

Fig. 11 is a perspective view illustrative of the welting after final molding as produced from the single fillet at the left of Fig. 8.

Referring now to the drawing and especially at present to Figs. 1 to 4 inclusive which are illustrative of one method of practising the improved method of manufacture of the invention, the reference numeral 20 indicates, in general, a double fillet of grain leather to be severed into two single fillets each of which is fashioned into a strand of beaded welting, it being understood that although as shown the fillet 20 is provided with an upper surface 21 of grain leather, the principles of the invention may be applied to less costly welting materials as well as to grain leather.

The fillet 20 has a width which is twice the width of either of the similar individual strands of welting to be fashioned therefrom and in accordance with the invention is first slit longitudinally and generally centrally of its width to form two overlapping flaps 22 and 23 one of which is joined to the fillet along what will be the inner edge of the welt extension of one of the strands of welting to be formed from the fillet, while the other flap is joined to the fillet at the inner edge of the extension of the other strand of welting. It will be observed that the flaps 22 and 23 are substantially coextensive in width, that is to say, prior to folding of the flaps each extends across the fillet substantially the full width of the other, each flap, in the instance shown, tapering towards its outer or free end or edge.

Any suitable form of knife or knives may be used to slit the fillet to form the flaps 22 and 23, the fillet being slit or cut along a transverse line 24 parallel to the upper surface 21, to form the bottom face of flap 23, while the fillet is cut along an upwardly sloping transverse line 25 to form the bottom face of flap 22 and upper face of flap 23.

The depth of the cut 24 beneath the upper or grain surface 21 of the fillet will vary in accordance with the thickness of the fillet but normally will be markedly less than one-half of the thickness thereof, lying either in or immediately below the fine grain texture at the grain surface, the cut 25 being sharply inclined with respect to said surface and emerging therefrom along a line just inside the welt extension at the right of Fig. 1. When the fillet is made of grain leather the upper face of the flap 22 will, of course, have a grain surface, while due to the fact that the cut 25 lies almost wholly within the fine grain texture at or near the upper surface 21, the upper face of flap 23 will have a texture not differing greatly from that of flap 22.

After the simple cutting or slitting operations described above, the flaps are ready for forming-up into beads without further treatment and those skilled in the art will readily recognize the great simplicity of these preliminary operations as compared to prior methods, the elimination of further cutting or slitting steps resulting in a considerable saving in time and expense; moreover, it will be observed that there is no waste stock.

The flaps are now broken upwardly and backwardly into the positions illustrated in Fig. 3 whereupon the bead fillers or cores 26 and 27 may be set in place in the angles formed between the flaps 22 and 23 and the shelf 28 formed by the parallel cut 24, the flaps being folded or molded around the bead cores into the position shown more particularly in Fig. 4, the thin outer ends of the flaps being pressed into

contact with the shelf 28. It will be understood that the cores 26 and 27 are cemented in place in the angles formed by the erected flaps while the latter are cemented not only to the cores but to the shelf 28 as well.

The channels 29 and 30, for the inseam stitches, may be cut either before or after the fillet is cut along the central vertical line 31 to form the two strands 32 and 33 of finished welting.

The bead cores may vary according to the final shape of the bead desired, those illustrated in Figs. 3 and 4 being conveniently formed out of a strand of stock 34 (Fig. 5) of square cross-sectional shape, the stock being slit along a diagonal line 35 to form the two cores of triangular cross-sectional shape.

The form of the invention shown in Fig. 6 differs principally from that of Figs. 1 to 4 inclusive in that, before the beads are formed-up, the two strands of welting 36 and 37 are severed from one another by a central longitudinally directed inverted V-shape cut which removes from the fillet a length of stock 38 of triangular cross-sectional shape which may be slit along the line 39 to form the bead cores. In this form of the invention the bead cores are not only formed from the fillet itself but the removal of the material from the inside lower corners of the sewing edges 40 and 41 leaves the latter desirably somewhat more flexible.

Figs. 8 to 11 inclusive illustrate a modified method not only of cutting a double fillet into two single fillets with bead forming flaps but likewise in the method of production of the bead cores. In this case a double fillet 42, of a width equal to the combined widths of the two strands of finished welting fashioned therefrom, is first severed along its central line as to produce the two single fillets 43 and 44 each of sufficient width for forming up a grain covered bead. The severing is accomplished by a three part cut comprising a lower vertical bar 45, a horizontal center bar 46 and an oblique upper bar 47, the latter emerging through the upper grain surface 48 while the vertical bar emerges through the lower flesh surface 49. The buried center bar 46 lies at a plane below the upper or grain surface 48 a distance less than half the thickness of the fillet and preferably immediately below the fine grain texture of said surface and extends horizontally from the upper end of the vertically directed bar a distance to the right to be hereinafter set forth, the upper bar extending obliquely upwardly from the outer end of the center bar, the upper bar being about twice as long as the center bar.

The lower vertical bar 45 passes longitudinally through the fillet centrally of the width of the latter and in cooperation with the other bars divides the fillet into two single fillets 43 and 44, each having an outwardly extending tapered lip at its upper inner edge. The amount of extension of these lips will vary in accordance with the width of the welting, those of $\frac{1}{2}$ " welting, for example, extending outwardly $\frac{3}{2}$ ". It will be observed that the lip 50 of the fillet 43 is provided with an upper face in the plane of the upper surface of the fillet and a lower face which slopes downwardly and inwardly, while the lip 51 of fillet 44 is provided with an upper face which slopes downwardly and outwardly and a lower face which is parallel to the upper surface of the fillet.

To prepare either of said single fillets for

forming-up into beaded welting as shown in Fig. 11, a single further cutting operation is required, each fillet being slit horizontally inwardly at the bottom edge of its respective lip to a point adjacent the inner edge of the welt extension, the knife used for said cutting operation having a cutting edge suitable for forming a longitudinally directed groove 52 in the upper face of the shelf 57, the groove being half way between the lateral edges of said face and said knife, in cutting the groove, leaving a bead 54 on the under sides of the flaps 55 and 56, which beads serve as fillers or cores for the welt beading when the latter is formed-up.

It will be noted that in this case the finished beads are somewhat smaller than in the forms shown in Figs. 1 to 7 inclusive. For this reason the flaps do not need to be as wide as those of Figs. 1 to 4 inclusive and Fig. 6. Since the lip 50 only partially overlies the lip 51, the latter may have an intact grain surface of sufficient area to completely cover the exposed surfaces of the bead formed from the flap 55. Upon completing the formation of the flaps 55 and 56 by the lateral incisions, the flaps are broken upwardly and backwardly for application of cement whereupon the moulder may set the cores 54 back into the corners formed by the flaps and the shelves 57 and 58, simultaneously folding the flaps and pressing the tapered outer edges thereof down into place on the shelves, crushing the welt to the final shape shown in Fig. 11. Preferably the grooves 52 are removed and the channels 59, for the inseam stitches, formed by molding the channels 59 in the welting, the material thereof being forced inwardly to fill the grooves 52.

In each of the several forms of the invention illustrated, the double fillet is of a width equal to the combined widths of the finished strands of welting formed therefrom and it will be observed that the tapered flaps, when cemented in place, form inner sewing edges on the welting which are somewhat thinner than the welt extensions and taper outwardly in a direction forming suitable attachment faces for a lasted upper.

The invention in its several forms is characterized by the fact that the flaps may be varied considerably in width to suit the size and weight of the beads to be formed and in all cases may be carried out with a minimum width of fillet and a complete lack of wasted stock. Those skilled in the art will recognize that through the use of bead fillers or cores of proper cross-sectional shapes, the shapes of the beads may be greatly varied without, however, the use of complicated cutting and slitting operations which have heretofore been necessary in the art.

While I have shown and described certain preferred forms which the invention may take, it will be understood that the same is not limited to the precise details described but is capable of variation and modification within the scope of the appended claims.

What is claimed as new, is:

1. The method of producing two welt strips from a double fillet of less width than the combined width of stock in single fillets required for the two beaded welts made from said strips, each strip being of greater overall width than one-half of the width of said fillet, comprising severing the fillet longitudinally by co-operating cuts including a cut lying in a plane parallel to the upper face of the fillet and extending at either side of the center line of the fillet to points adjacent the inner edges of the welt extensions of the welt strips, a cut lying in a plane oblique to the upper face of the fillet and extending upwardly from the parallel cut and emerging from said upper face along a line which defines the overall width of one of the single fillets, the oblique cut intersecting the parallel cut to define the width of the other fillet, and a cut extending from the parallel cut at the center of the fillet towards and emerging through the bottom face of the fillet.
2. The method according to claim 1 in which the oblique cut intersects the parallel cut intermediate the ends of the latter.
3. The method according to claim 1 in which the oblique cut extends substantially equal distances towards either side of the center line of the fillet and intersects the parallel cut intermediate the ends of the latter.
4. The method according to claim 1 in which the oblique cut intersects the parallel cut at one of the side edges of the latter.
5. The method according to claim 1 in which the oblique cut extends substantially equal distances towards either side of the center line of the fillet and intersects the parallel cut at one of the side edges of the latter.
6. The method according to claim 1 in which the parallel cut lies closer to the upper face of the fillet than to the lower face.
7. The method according to claim 1 in which the last named cut is of inverted V-shape, the apex of the V lying in the parallel cut.
8. The method according to claim 1 in which the last named cut is normal to the bottom face of the fillet and midway between the side edges thereof.
9. The method of making beaded welting which comprises forming a flap by slitting the fillet longitudinally through an edge face of the fillet substantially parallel to the upper face thereof, and simultaneously forming a longitudinal rib on the inner face of the flap and a groove on the opposed face of the shelf underlying the flap, the unslit portion of the fillet forming the welt extension, lifting the flap and cementing the exposed faces, folding the flap and simultaneously forcing the rib into the corner formed by the lifted flap to form a bead and pressing the remainder of the flap into contact with the face of the fillet formed by the slit.

WILLIAM C. VIZARD.
